SKI POLES

Henry J. Barrea, 925 Prospect Place, Brooklyn 13, N.Y.
Filed Nov. 4, 1963, Ser. No. 320,996
6 Claims. (Cl. 280—11.37)

The present invention relates to an improved ski pole as used in the sport of skiing.

Ski poles should be strong and light weight to facilitate their easy manipulation and safe use. They are commonly formed of tubular metal poles or shafts tapered at their lower ends to points and provided at their upper ends with handle members. In order to limit the penetration of the pointed end of the ski pole into the snow a laterally projecting snow engaging member is mounted on each ski pole a short distance above the tip thereof. These snow engaging members are commonly in the form of rings concentric with the ski pole and connected thereto radial straps or by a web and a hub section.

It is important that while the over-all snow ring should be flexible, the connection thereof to the pole should be firm and secure so as not to permit any relative movement or slipping thereof. Many expedients have been employed for securing ski rings to ski poles but these have possessed many drawbacks and disadvantages. The required firm connection of the snow ring has been usually difficult and costly to achieve and frequently has weakened the lower section of the ski pole and the resulting assembly has left much to be desired.

In the present invention I provide a ring connection which employs a resilient sleeve as a gripping member. This of itself is, of course, not new. However, a serious defect in prior sleeves has been their relative fragility since when stretched, they tend to tear easily. Further, being generally of resilient rubber, the deteriorating action of the sun makes them short lived. This problem has existed for many years without any solution to my knowledge.

It is therefore a principal object of the present invention to provide an improved ski pole construction which provides improved assembly of a snow ring to a ski pole and which overcomes the above defect.

Still another object of the present invention is to provide an improved fastening device as used in such assembly.

A further object of the present invention is to provide an improved ski pole of the above nature characterized by strength, reliability, lightness and low cost, as well as resistance to such wear and deterioration as above described.

The above and other objects of the present invention will become apparent from a reading of the following description taken in conjunction with the accompanying drawing wherein:

FIGURE 1 is a front perspective view of a ski pole embodying the present invention;

FIGURE 2 is an enlarged fragmentary vertical medial longitudinal sectional view thereof;

FIGURE 3 is a top plan view of the ski ring member;

FIGURE 4 is a top plan view of the securing member;

FIGURE 5 is a sectional view taken along line 5—5 of FIGURE 4;

FIGURE 6 is a fragmentary vertical medial longitudinal sectional view of a modified embodiment; and

FIGURE 7 is a perspective view of the snow ring of the modified embodiment, and showing its integral elastomeric locking sleeve, the collar having been removed for purposes of clarity.

In a sense the present invention contemplates the provision of a ski pole comprising an elongated shaft having a bottom section tapered toward the free end thereof, a

2

snow engaging member having an opening therein registering with said tapered section above said free end thereof, an elastomeric sleeve engaging said bottom section below said snow engaging member, and a relatively rigid collar engaging and compressing said sleeve.

According to one form of the present device, an abutment defining annulus having an inside diameter smaller than the maximum diameter of the shaft bottom section is force fitted onto the tapered section and is located below the top thereof. The snow engaging member includes a ring connected by radial spokes or the like to an apertured central hub which registers with the shaft tapered section. In said one form the elastomeric sleeve terminates at its top in a peripheral flange which bears against the underface of the snow ring hub and the lower end of the sleeve is provided with a peripheral lip overlying the bottom edge of the sleeve confining collar and of a diameter which is greater than the inside diameter of the collar so as to serve as additional locking means.

10 Referring now to the drawing which illustrates the first embodiment of the present invention, the reference numeral 10 generally designates the improved ski pole which includes an elongated tubular shaft 11 formed of a strong, light weight material such as aluminum or the like. The shaft 11 is provided at its lower end with an integrally formed bottom tapered section 12 terminating in a snow penetrating point or tip 13. The remainder of the shaft 11 may be slightly tapered or of uniform cross-section. A handle member 14 of any conventional construction is attached to the upper end of the shaft 11 and carries a flexible hand receiving loop or strap 16.

A snow engaging assembly 18 is positioned on the upper part of the bottom tapered section 12 and includes an abutment member 19, a snow ring 20 and a locking device 21. The abutment member 19 is a washer or annulus which may be likewise formed of aluminum and has an inside diameter slightly less than that of the maximum diameter of the bottom tapered section 12. The annulus 19 registers with the section 12 and is force-fitted to the upper part thereof as will be hereinafter set forth.

The snow ring 20 may be integrally formed of a flexible material, for example a low density polyethylene or polypropylene or similar material, and is in the shape of a wheel including a cylindrical central hub 22, having an axial bore 23 formed therein which has an inside diameter approximately that of the annulus 19. Radiating from the hub 22 are a plurality of spokes 24 which support and are joined at their outer ends to a ring section 26 of substantially circular transverse cross section. The snow ring 20 directly underlies the annulus 19, the axial bore 23 registering with the tapered section 12 and the upper face of the hub 22 abutting the annulus 19.

The locking device 21 underlies the hub 22 and comprises a sleeve 27 tightly engaging the tapered section 12 and terminating at its upper end in a peripheral flange 28 the top face of which bears upon the underface of the hub 22. The sleeve 27 may be formed of any suitable elastomeric material such as natural or synthetic rubber.

A most important aspect of this invention is the provision of the rigid collar 29 which surrounds the sleeve 27 and maintains it in a radially compressed condition. The collar 29 may be formed of aluminum or other suitable material. The lower end of the sleeve 27, in the assembled condition of the ski pole, is formed with a peripheral lower lip 30 which overlies the bottom edge of the collar 29 and is of a diameter greater than the inside diameter of collar 29 so as to provide additional locking means.

70 The collar 29 serves a plurality of functions in the device. First, and as is most apparent, it assures a firm and secure coupling among the various components and fa-

cilitates their simple and rapid assembly with a minimum of skill. However, a more important advantage is provided in that it protects the longitudinally tensioned elastomeric sleeve 27 from rapid deterioration which is normally consequent to the exposure of rubber and the like to outdoor weathering conditions including ultra-violet radiation and other deteriorating influences. Collar 29 also prevents damage to the sleeve 27 by abrasion or the like by ice and other objects which the ski pole may encounter in use.

In applying the snow ring assembly to the ski pole shaft 11, the shaft 11 is inverted and the annulus 19 and hub 22 are slipped onto the tapered section 12. The locking member 21 which includes the collar 29, is then pressed over the tip 13 downwardly toward the hub 22, the flange 28 confronting the hub 22. A tubular tool having an inside diameter approximately that of the collar 29 is then coaxially applied to the free end face of the collar 29, the tapered section 12 telescoping into the tool. Pressure is then applied to the tool or the tool is struck to advance the locking member 21 toward the hub 22 and to advance the hub 22 and annulus 19, thereby effecting a force fit of the annulus 19 on the tapered section 12 and a tight and secure sandwiching of the ring hub 22 between the annulus 19 and the flange 28.

During the advance of the sleeve 27 it is tensioned and is stretched to beyond the outer edge of the collar 29. Upon release of the axial pressure on the collar 29, the sleeve 27 tends to contract axially and it expands radially to form the collar edge protecting lip 30 and to effect a radial compression of the sleeve 27 as confined by the collar 29 and hence a tight non-slipping connection between the locking device 21 and the shaft tapered section 12. It should be noted that the normal unstressed inside diameter of the sleeve 27 is less than the outside diameter of the registering part of the tapered section 12 so that the sleeve 27 is, in the complete assembly, also under peripheral tension as well as under some longitudinal tension.

In the embodiment shown in FIGURES 6 and 7, the snow ring 30a comprises a metal wheel 31 to spaced portions of which is connected a web or spider 32 as is more or less conventional. However, the sleeve 33 is integral with web 32, these elements being of live rubber or other elastomeric material. Sleeve 33 depends downwardly so as to serve the same function as sleeve 27 in the previous embodiment. Collar 34 serves the same function as previously described collar 29, it being in the same form thereof.

Accordingly the second embodiment described has the same advantages as the first embodiment and has an added advantage in that the sleeve 33 is integral with the snow ring web, thereby not only enhancing the locking effect thereof but simplifying the assembly.

While there have been described and illustrated preferred embodiments of the present invention, it is apparent that numerous alterations, omissions and additions may be made without departing from the spirit thereof. For example, the integral sleeve 33 may be reversed in direction on the shaft by simply reversing the snow ring 30a so that the sleeve is over rather than under the web 32.

What is claimed is:

1. A ski pole comprising an elongated shaft having a

bottom section tapered toward the free end thereof, a snow engaging member having an opening therein registering with said tapered section above said free end thereof, an elastomeric sleeve engaging said bottom section as well as said snow engaging member for securing said snow engaging member to said shaft, and a relatively rigid collar engaging and compressing said sleeve, said collar being open at both ends thereof and locking said sleeve and said snow engaging member to said shaft.

2. A ski pole comprising an elongated shaft having a bottom section tapered toward the free end thereof, a snow engaging member having an opening therein registering with said tapered section above said free end thereof, an elastomeric sleeve engaging said bottom section below said snow engaging member, a relatively rigid collar embracing and compressing said sleeve, and a peripheral lip on said sleeve projecting beyond the lower edge of said collar and of a diameter greater than the inside diameter of said collar.

3. A ski pole comprising an elongated shaft having a bottom section tapered toward the free end thereof, an abutment member having an opening thereon tightly engaging said bottom section, a snow ring having an apertured hub engaging said bottom section and abutting the underface of said abutment member, an elastomeric sleeve engaging said bottom section below said hub and terminating at its upper end in an integral peripheral flange bearing on the underface of said hub, and a relatively rigid collar embracing and compressing said sleeve below said flange, said collar being open at both ends thereof and locking said sleeve and said snow engaging member to said shaft.

4. A ski pole comprising a rigid shaft, a snow engaging member on said shaft, and fastening means for securing said snow engaging member to said shaft, said means comprising an elastomeric sleeve depending from said snow engaging member and an outwardly exposed rigid collar embracing and compressing said sleeve against said shaft, said collar being open at both ends thereof and locking said sleeve and said snow engaging member to said shaft.

5. A ski pole according to claim 4 and wherein said sleeve is under both peripheral and longitudinal tension on said shaft, and a lower peripheral lip on said sleeve projecting beyond the lower edge of said collar and of a diameter greater than the inside diameter of said collar.

6. A ski pole according to claim 5 and wherein said sleeve is integral with said snow engaging member and depends downwardly therefrom.
